FACE PROTECTING BREATHING MASK OR THE LIKE

Sally G. Lloyd and Lois G. Crawford, both of Box 1357, Bradenton, Fla.

Filed Apr. 28, 1965, Ser. No. 85,005

Term of patent 14 years

(Cl. D83—1)

FIG. 1 is a perspective view of a face protecting breathing mask, embodying our new design;

FIG. 2 is a top plan view thereof;

FIG. 3 is a bottom plan view thereof;

FIG. 4 is a side elevational view thereof, the opposite side elevational view being substantially the same.

FIG. 5 is a front elevational view thereof; and

FIG. 6 is a rear elevational view thereof.

We claim:

The ornamental design for a face protecting breathing mask or the like, substantially as shown.
